US0D1112867S

(12) **United States Design Patent** (10) Patent No.: **US D1,112,867 S**
(45) Date of Patent: ** Feb. 10, 2026

(54) **CAR LIGHT**

(71) Applicant: **SHENZHEN WELL-DONE INDUSTRIAL CO., LTD.**, Shenzhen (CN)

(72) Inventor: **Dongna Zhou**, Shenzhen (CN)

(73) Assignee: **SHENZHEN WELL-DONE INDUSTRIAL CO., LTD.**, Shenzhen (CN)

(**) Term: **15 Years**

(21) Appl. No.: **29/907,041**

(22) Filed: **Jan. 3, 2024**

(30) **Foreign Application Priority Data**

Dec. 4, 2023 (CN) 202330797545.X

(57) **CLAIM**

The ornamental design for a car light as shown and described.

DESCRIPTION

FIG. 1 is a perspective view of car light showing my new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines in the drawings depict portions of the car light that form no part of the claimed design.

1 Claim, 8 Drawing Sheets
